UNITED STATES PATENT OFFICE

FREDERICK A. WARREN AND EDGAR A. HORNBY, OF FLANDREAU, SOUTH DAKOTA

YARDAGE INDICATOR OR MARKER FOR FOOTBALL GRIDIRONS

Application filed April 10, 1930. Serial No. 443,167.

This invention relates to marking devices and particularly to means for marking and indicating the yard lines on a football playing field. At the present time, on "grid-
5 irons" or football fields, markers are used on each side of the football field showing the different yard lines, these markers being made out of metal. Sometimes in place of these markers, stakes are used and in almost
10 every game, some of the players are rushed out of bounds and by chance fall on these markers and are injured thereby.

One of the objects, therefore, of my invention is to provide a marker adapted to be
15 used at the side of the football field which is made of rubber and which, therefore, cannot injure any player striking it or falling upon it.

A further object is to provide a marker
20 of this character which is so constructed as to provide a plurality of sides, each side containing the number denoting the yard line with which the marker is associated, these numbers being so disposed that the spectators
25 may see the number of the yard line from any portion of the field, thus particularly in a stadium where the spectators are seated all around the field, conveying to the spectators the exact location of where a ball
30 is put in play, where it is placed out of bounds, much more readily than where numbers are placed on only one side of the field, these markers also being of such dimensions and form as to be readily observable by the
35 players themselves at a glance to either side of the field.

Other objects will appear in the course of the following description.

Our invention is illustrated in the accompanying drawings, wherein:—

Figure 1 is a diagrammatic representation of a portion of a playing field or gridiron showing our markers in place;

Figure 2 is an elevation of a marker constructed in accordance with our invention;

Figure 3 is a vertical sectional view thereof.

Referring to Figures 2 and 3, it will be understood that the improved marker is to be made of rubber in the form of a many-sided

body portion 10 and a top wall 11. The marker is hollow and the side walls 10 are thicker at their edges than at their upper portions where they merge into the top portion 11. Preferably, for instance, though we
55 do not wish to be limited to these dimensions, the marker will have a total height of about fourteen inches and a width at its base of fourteen inches, while the walls 11 will be five-sixteenths of an inch at their lower
60 edges, thinning upward to three-sixteenths of an inch where they join the top 11. The top 11 may be made in one piece with the sides or of a separate piece and cemented to the sides or attached thereto in any suitable
65 manner. The top 11 is preferably upwardly and centrally rounded and formed at its apex with an aperture 12 through which a finger
70 may be passed to shift the markers when ever desired.

The markers are designed to rest upon the ground opposite each yard line 13 on the playing field A and markers will also preferably be disposed opposite the goal line 14. The markers 10 upon their several sides will
75 display a number indicating the yardage from the middle line of the field to a goal, as for instance 40, 30, 10, etc. The marker shown in Figures 2 and 3 has thereon the numeral 10 arranged on all four sides of the
80 marker. While we preferably make markers square in cross section, we do not wish to be limited to this, as the markers might have other forms in cross section. Preferably
85 the top will be rounded, but we do not wish to be limited to this. Markers of this character will be observable from all parts of a stadium, for instance, or other field within
90 which the game is played, both by the spectators and the players whereas markers that lie flat upon the ground like the metal markers ordinarily used are not readily observable from different points of a stadium. These markers are observable from either the ends
95 of the stadium or from the sides of the stadium and preferably two series of markers will be used, one on each side of the gridiron. Inasmuch as the markers are of rubber and hollow, they cannot injure any player who

may accidentally strike against them or fall upon them.

While we have heretofore referred to rubber as being the material from which the markers are to be made, it is to be understood that any equivalent material might be used, that is, material which would have sufficient stiffness to stand up and retain its shape and yet sufficient softness as to prevent injury when run into by a player.

10 10 We claim:

1. A marker of the character described formed of a hollow india rubber body, having sufficient elasticity to be readily bent upon itself, but sufficient rigidity to stand upright, the marker being formed with a plurality of side faces, each face having thereon a numeral indicating the yardage of a particular yard line on a playing field.
- 15 2. A marker of the character described, square in cross section and hollow, the marker being made of rubber and having an upwardly rounded top portion formed with a central aperture, the side faces of the marker displaying numerals indicating distance from a yard line to a goal.
- 20 3. As an article of manufacture, a marker for football fields formed from a hollow body of rubber, the marker being many sided in cross section and having each face displaying the same numeral indicating distance from a yard line to a goal, the top of the marker being upwardly rounded and having a central aperture.
- 25 4. A marker of the character described formed of a hollow body of rubber having sufficient elasticity to be readily deformed, but sufficient rigidity to stand upright, the marker being formed with a plurality of integral walls and having an upwardly rounded top wall, the sides of the marker extending downward and outward for the display of indicia thereon, the marker resting entirely on the lower edges of the side walls and being of sufficient cross sectional area to permit it to rest thereon in a position of stable equilibrium.
- 30 5. A marker of the character described formed of a hollow body of elastic material, the body having downwardly extending side walls adapted to rest upon the ground, the body as a whole having sufficient elasticity to be readily deformed but sufficient rigidity to stand upright, the marker being of sufficient cross-sectional area to permit it to rest on its side walls in a position of stable equilibrium.

In testimony whereof we hereunto affix our signatures.

60 FREDERICK A. WARREN.
EDGAR A. HORNBY.
